FEELER MECHANISM FOR LOOMS.

1,250,380.

Specification of Letters Patent. Patented Dec. 18, 1917.

Application filed February 2, 1916. Serial No. 75,801.

To all whom it may concern:

Be it known that I, EDWARD S. STIMPSON, a citizen of the United States, and resident of Hopedale, county of Worcester, State of Massachusetts, have invented an Improvement in Feeler Mechanism for Looms, of which the following description, in connection with the accompanying drawing, is a specification, like characters on the drawing representing like parts.

This invention relates to improvements in feeler mechanisms for looms in which the feeler comprises two relatively movable members acting upon the filling carrier of the active shuttle and adapted to be moved relatively to one another upon substantial exhaustion of filling and thereby to initiate the action of mechanism for causing a change in the operation of the loom.

In feeler mechanisms of this type the relative movement between the members of the feeler is small and it is desirable therefore that the same be positioned properly in respect to the path of the filling carrier in order to insure the effectiveness of the feeler mechanism. If shuttles of slightly different heights are used in the loom or for any other reason the axis of the filling carrier lies above or below the central horizontal plane of the feeling members, a failure of detection of substantial absence of filling is likely to result.

One of the objects of the present invention is to provide a feeler of this type with means whereby the yarn-engaging end of the feeler members will be moved automatically vertically upon engagement with the yarn mass upon the filling carrier to position the same properly with respect to the path of the filling carrier.

Another object of the invention is to provide means for more delicately adjusting the coöperating elements of the feeler.

Another object of the invention is to provide means whereby a slight relative movement between the feeler members will cause a relatively extensive movement adapted to actuate a transmitter for positioning the controlling latch in the path of the moving actuator.

Another object of the invention is to provide a novel form of transmitter in which the elevating of one member of the transmitter by the feeler mechanism will cause

the elevation of the opposite end of the transmitter member to raise the controller latch into the path of a moving actuator.

Another object of the present invention is to provide a simple form of feeler mechanism which may be readily applied to a usual type of loom and which will increase the efficiency of the loom.

Other objects of the invention will more fully appear from the following description and accompanying drawings and will be pointed out in the annexed claims.

In the drawings:

Figure 1 is a plan view, centrally broken away, of a usual form of Northrop loom with a preferred form of the feeler mechanism embodying the present invention applied thereto.

Fig. 2 is a view of the feeler mechanism and transmitter looking toward the end of the feeler,

Fig. 3 is a plan view of the feeler casing or guide and the feeler members mounted therein,

Fig. 4 is a vertical longitudinal sectional view through the feeler guide showing the reciprocating members in elevation,

Fig. 5 is a side elevation of the feeler mechanism showing the same engaged by the filling carrier and positioned to effect a change in the operation of the loom, and,

Fig. 6 is an end view of the feeler, a portion of the casing being broken away and shown in section.

A preferred embodiment of my invention is illustrated herein as applied to the Northrop type of loom, the parts shown, which are of well known construction, comprising the breast beam 1, the lay 2, having the usual shuttle boxes 3 and 4, the hopper or battery 5 adapted to contain a plurality of filling carriers, the transfer arm 6 operable through the usual mechanism not shown, which is governed through the controller shaft 7 and controller latch 7^a, by mechanisms for detecting absence or failure of filling including the weft fork feeling mechanism 8.

The shuttle box 3 is shown as containing the running shuttle 10 provided with a bobbin 11 which has a plain cylindrical barrel 12 upon which the filling 13 is wound uniformly and without the usual feeling "bunch." The shuttle and shuttle box are,

of course, provided with the usual aligned apertures 14, 15 to afford the feeler access to the bobbin.

The feeler stand 16 is adjustably secured 5 to the shipper stand 17 by a bolt and slot connection 18, 19, the top 20 of said feeler stand preferably being provided with a groove 21 to receive a rib projecting downwardly from the lower plate 22 of the feeler 10 casing or guide, which together with a lateral extension 23 of the upper member of the feeler casing may be adjustably secured to the feeler stand by bolts 24 extending through elongated slots 25 in said stand.

15 The upper and lower members of the feeler casing may conveniently be secured together to permit the removal of the feeler mechanism as a whole by one or more screws 26.

20 The main portion of the feeler casing may conveniently be constructed in the form of a rectangular guideway, the bottom 27, the side 28, and ends 29 and 30 preferably being formed integrally with the extensions 22. The opposite vertical side 31 and top 32 may also be formed integral with the extension 23, the top 32 desirably being provided with an integral boss 33 adapted pivotally to support a cam, the purpose of 30 which will hereinafter be described.

The feeler which enters the shuttle and "feels" upon the bobbin or other filling carrier may, in so far as this invention relates broadly to means for automatically positioning the feeler properly in respect to the filling carrier, be of substantially any type comprising two relatively movable members which enter the shuttle and are actuated by engagement with the filling carrier therein 35 until substantial exhaustion of filling, detected by one of said members, causes a relative movement between said feeling members which is utilized to initiate the action of mechanism for effecting a change in the 40 operation of the loom, since the broad principle involved herein resides in mounting the horizontal reciprocable feeling members in such a manner as to permit a free vertical movement of their filling engaging 45 ends; and in so designing the end of one, that upon engagement with the yarn mass 50 on the bobbin, it will instantly raise or lower the filling engaging ends of both to the most effective position. This may conveniently be accomplished by providing the 55 yarn engaging member with a reentrant, preferably concave, face adapted circumferentially to engage the cylindrical surface of the yarn upon the bobbin so that upon contact therewith the feeler will be raised or 60 lowered until the horizontal central plane of the yarn engaging face substantially coincides with the path of movement of the axis of the bobbin.

65 While this principle of construction may

be of general application it is illustrated herein as applied to a preferred form of feeler which comprises a yarn impinging member 35 preferably constructed of two hollow complementary halves secured together by rivets or screws 36 presenting a concave or other reentrant yarn engaging face 37 and telescopically inclosing a relatively movable penetrating member 38, the end of which preferably is in the form of a 75 vertical knife-edge 39 normally lying substantially in the plane of the extremities of the reentrant face of the yarn impinging member.

The yarn impinging member of the feeler 80 is provided with a body portion 40, slidably mounted in an aperture 41 in the end 29 of the casing and is maintained normally in extended position by a helical spring 42 abutting at one end against the inner face 85 of the casing end 29 and at the other end against an external shoulder or flange 43 on the body 40. The outer end of the body 40 is provided with a flange 44, of greater diameter than the aperture 41 in the casing, 90 which, abutting against the outer face of the end 29 limits the movement of the yarn impinging member of the feeler.

The flange 44 preferably is provided with a curved face 45 bearing against the end 95 29 of the casing adapted to permit a vertical rocking movement of the yarn impinging member.

The opposite end 30 of the casing is provided with an aperture 46 of greater vertical width than the thickness of the extension or yarn impinging member which passes through it so that the latter may have a free vertical movement. The extended portion of the impinging member 105 35 is preferably tapered so that as it is being thrust into the casing it will have an increasing amplitude of vertical movement which will enable it readily to be properly positioned on the filling carrier notwithstanding the arcuate path of the axis of the filling carrier.

A plunger 47 resting upon a spring 48 in a vertical aperture in a boss 49 on the casing 27 is preferably provided to support the 115 yarn impinging member in substantially normal position while permitting the same to be raised or lowered when the reentrant end 37 of the member engages the filling upon an inaccurately positioned bobbin.

The halves of the body portion 40 of the impinging member are provided near its extension 35 with bosses 50 between which the elbow 51 of a bell crank lever is pivoted, one arm 52 of said lever depending in the 125 path of a shoulder or head 53 on the penetrating member, the other arm 54 of said lever being adapted to engage the end 55 of a transmitter arm when the penetrating member is moved relatively to the yarn im-

pinging member of the feeler. A helical spring 56 located in the chamber 57 is seated at one end upon the end of an adjusting screw 58 and abutting at its opposite end, 5 against the arm 52 of the bell crank lever, which in turn engages the head 53 on the penetrating member 38, serves the double purpose of maintaining the end of the penetrating member normally projected beyond 10 the concave face 37 of the impinging member and also of retaining the bell crank arms 52, 54 normally in the inoperative position shown in Fig. 4. By advancing or 15 retracting the screw 58 the amount of resistance imposed upon the penetrating member 39 may be regulated to conform to the character of the filling being used.

A screw 59 extending obliquely through the bosses 50 and having its end engaging 20 the arm 52 of the bell crank lever provides a still further means for accurately adjusting the normal position of the parts.

In the operation of the machine the yarn impinging member 35 and the penetrating member 39, which is telescopically carried thereby, enter the shuttle upon each beat up of the lay, the reentrant end of the former positioning the parts properly in relation to the path of the axis of the bobbin while the 30 penetrating member enters the yarn mass between adjacent spirals of the yarn of which it is composed. Upon further movement of the lay both the yarn impinging member and the penetrating member are 35 carried forward together, without relative movement therebetween so that the bell crank lever is not actuated to engage the transmitter. When however, the penetrating member 39 encounters an impenetrable 40 medium such as the barrel of the bobbin it will be forced inwardly relatively to the inclosing yarn impinging member, thus actuating the arm 52 of the bell crank lever and raising the transmitter engaging arm 54.

45 Inasmuch as this movement by the feeler of the transmitter engaging arm is relatively slight, and also because a relatively strong force is required to actuate the transmitter, an adjustably mounted cam mechanism is 50 provided herein which may be accurately positioned in respect to the transmitter engaging arm of said bell crank lever, and which will amplify the movement thereof to effectively actuate the transmitter.

55 As illustrated herein this mechanism comprises a substantially horizontal member 60 having an upwardly extending lug 61 which is pivotally mounted upon a bolt 62 extending through the lug 33 on the casing, 60 one end of said member 60 being provided with an inclined or cam surface adapted to engage a stud 64 which projects laterally from the transmitter engaging arm 54 when the latter is raised by the aforesaid relative 65 movement of the penetrating member to the

impinging member, so that further movement of the feeler members in unison will cause the lug 64 to ride up over the inclined face 63 thereby positively forcing the end 55 of the transmitter upwardly.

70 In order to insure co-operative relation between the lug 64 and the member 60 notwithstanding the slight relative movement between the yarn impinging and penetrating members, the lug 64 desirably is formed with 75 a flat horizontal upper face and a curved lower face, forming at their junction an edge beneath which engagement with the inclined portion 63 of the member 60 will be effective.

80 The member 60 also preferably is made adjustable so that it may be positioned accurately in respect to the lug 64. As illustrated herein this is accomplished by providing an extension or tail 65 of said member 60 with an adjusting screw 66 bearing upon the top of the casing and interposing a spring 67 between the lug 61 on said member 60 and a suitable abutment 68 on the casing, which may be an offset portion of 90 the lug 33, in such a manner as to retain the end of the adjusting screw in contact with the casing while permitting the member 60 to rock about its pivot as the lug 64 rides up over the same.

95 It will be noted that the feeler mechanism heretofore described, upon detection of substantial exhaustion of filling raises the adjacent end of the transmitter 55, instead of depressing it as is usual in looms in which 100 the controller latch 7^a is raised into the path of the weft hammer 9 or other moving actuator. The present invention therefore includes a novel form of transmitter in which 105 the elevation of the end engaged by the feeler member will simultaneously raise the controller latch.

110 The preferred form of transmitter illustrated herein comprises a stand 70 which may be adjustably secured to a boss 71 on the shipper stand 17 on the breast beam 1 or an extension thereof, said stand having a pair of adjacent studs 72, 73 upon which inter-engaging toothed members or segmental gears 74, 74^a are mounted, said toothed 115 members being provided with oppositely disposed bosses or sockets 75, 76 in one of which is seated the transmitter arm 55 which is engaged by the arm 54 of the bell crank lever of the feeler mechanism, the other boss 120 or socket 76 supporting an arm 77 underlying the usual controller latch 7^a. It will be obvious that by this construction the raising of the end of the transmitter arm 55 will cause the elevation of the opposite end of 125 the arm 77 thereby raising the controller latch into the path of the weft hammer so that upon the next forward movement of the latter transfer of the filling carrier in the running shuttle or such other change in the 130

operation of the loom as may be called for by the usual mechanisms, will be effected.

In the operation of the loom, as will be obvious from the foregoing description, the filling carrier upon the beating up of the lay will be engaged by the end of the impinging member 35 of the feeler mechanism, the re-entrant end of said member acting to position properly said member in relation to the path of the axis of the filling carrier. When the filling is nearly exhausted the penetrating member 38 will be engaged by the barrel of the filling carrier and will be moved relatively to the impinging member thereby actuating the arm 52 of the bell crank lever, raising its transmitter engaging arm 54 so that the stud 64 will ride up over the inclined or cam surface 63 upon the member 60, thereby elevating the end of the transmitter arm 55.

This arm moving upon its pivot 72 will cause the member 78* to raise the opposite arm 77 of the transmitter and through it elevate the controller latch 7^a into the path of the vibrating actuator, the weft hammer 9 thus initiating the action of the transfer mechanism or effecting such other change in the operation of the loom as may be called for.

30 The adjustability of the cam member 60 which amplifies the movement of the transmitter engaging arm 54 permits a very delicate positioning of the parts which will insure the operation of the transfer mechanism 35 even though the relative movement between the penetrating member 39 and the impinging member 35 be very slight.

It will be understood that the mechanism described herein is an illustrative embodiment of my invention and is not restrictive and that various changes in construction and arrangement of parts may be made within the spirit and scope of the following claims.

45 Having thus described my invention, what I claim as new and desire to secure by Letters Patent is:

1. Controlling mechanism for looms comprising horizontally reciprocable and vertically movable members adapted to enter an active shuttle and feel upon the filling mass of a filling carrier therein, means for automatically positioning said members in the path of the axis of the filling carrier, means 50 for causing relative movement between said members upon detection of substantial absence of filling upon said filling carrier and means operable by the relative movement of said members for initiating the action of mechanism for effecting a change in the operation of the loom.

2. Controlling mechanism for looms comprising horizontally reciprocable and vertically movable impinging and penetrating members adapted to enter an active shuttle

and feel upon the filling mass of a filling carrier therein, means for automatically positioning said members in the path of the axis of the filling carrier, means for causing relative movement between said impinging and penetrating members upon the engagement by the said penetrating member with an impenetrable medium on the filling carrier and means operable by said relative movement to initiate the action of mechanism for effecting a change in the operation of a loom.

3. Controlling mechanism for looms comprising a horizontally reciprocable and vertically movable impinging member having a reentrant face adapted, upon the beating up of the lay, circumferentially to engage the yarn mass upon the filling carrier of an active shuttle and to be reciprocated thereby, a spring actuated penetrating member telescopically mounted within said impinging member and having its end projecting within the limits of said reentrant face adapted to be moved relatively to said impinging member when engaged by an impenetrable medium on said filling carrier, and means actuated by said relative movement to initiate the action of mechanism for effecting a change in the operation of the loom.

4. Controlling mechanism for looms comprising a horizontally reciprocable and vertically movable impinging member having a reentrant face adapted, upon the beating up of the lay, circumferentially to engage the yarn mass upon the filling carrier of an active shuttle and to be reciprocated thereby, a spring actuated penetrating member having a vertical edge, adapted to enter between adjacent spirals of the yarn upon the filling carrier, located within the limits of said reentrant face and adapted to be moved relatively to said impinging member when engaged by the barrel of said filling carrier and means operable by said relative movement to initiate the action of mechanism for effecting a change in the operation of the loom.

5. Controlling mechanism for looms comprising a horizontally reciprocable and vertically movable impinging member having a reentrant face adapted, upon the beating up of the lay, circumferentially to engage the yarn mass upon the filling carrier of an active shuttle and to be reciprocated thereby, a spring actuated penetrating member telescopically mounted within said impinging member and having its end projecting within the limits of said reentrant face, adapted to be moved relatively to said impinging member when engaged by an impenetrable medium on said filling carrier, a bell crank lever mounted upon said impinging member operable by the relative movement of said penetrating

130

member to actuate mechanism for effecting a change in the operation of the loom.

6. A controller for looms comprising a horizontally reciprocable spring actuated and vertically movable yieldably supported 5 yarn impinging member having a reentrant face, a penetrating member telescopically mounted within said impinging member and movable relatively thereto upon engagement with an impenetrable medium on said filling carrier, a bell crank lever pivotally mounted upon said yarn impinging member and having one arm projecting in the path of said penetrating 10 member and the other arm adapted to engage a transmitter for operating mechanism to effect a change in the operation of the loom and a spring within said impinging member operatively located normally to retain 15 said bell crank lever in inoperative position and the penetrating member in extended position.

7. A controller for looms comprising a horizontally reciprocable spring actuated and vertically movable yieldably supported 20 yarn impinging member having a reentrant face, a penetrating member telescopically mounted within said impinging member and movable relatively thereto upon engagement with an impenetrable medium on said filling carrier, a bell crank lever pivotally mounted upon said yarn impinging member and having one arm projecting in the path of said penetrating member and the other arm 25 adapted to engage a transmitter for operating mechanism to effect a change in the operation of the loom and a spring within said impinging member operatively located normally to retain said bell crank lever in 30 inoperative position and the penetrating member in extended position, and means for adjusting the pressure upon said spring whereby the same may be regulated to control the force required to cause relative 35 movement between the penetrating and the impinging members.

8. Controlling mechanism for looms comprising a guide, a horizontally reciprocable and vertically movable yarn impinging 40 member mounted therein, a penetrating member carried by said yarn impinging member and movable relatively thereto upon engagement with an impenetrable medium on said filling carrier upon substantial exhaustion of filling, means operable by said 45 relative movement to engage a transmitter, and means operable by the continued movement in unison of said penetrating and impinging member to amplify the movement 50 of said transmitter.

9. Controlling mechanism for looms comprising a guide, a horizontally reciprocable and vertically movable yarn impinging member mounted therein, a penetrating 55 member carried by said yarn impinging

member and movable relatively thereto upon engagement with an impenetrable medium on said filling carrier upon substantial exhaustion of filling, a bell crank lever pivotally mounted upon said impinging member 60 operable by said relative movement to engage a transmitter for causing the actuation of mechanism to effect a change in the operation of the loom and a cam engaged by said bell crank lever when actuated by said relative movement to amplify the movement of 65 said transmitter.

10. Controlling mechanism for looms comprising a guide, a horizontally reciprocable and vertically movable yarn impinging 70 member mounted therein, a penetrating member carried by said yarn impinging member and movable relatively thereto upon engagement with an impenetrable medium on said filling carrier upon substantial exhaustion of filling, a bell crank lever pivotally mounted upon said impinging member 75 operable by said relative movement to engage a transmitter for causing the actuation of mechanism to effect a change in the operation of the loom, a cam consisting of a member pivotally mounted upon said guide and having an inclined face adapted to engage said bell crank lever and resilient means for permitting a pivotal movement of 80 said cam.

11. Controlling mechanism for looms comprising a guide, a horizontally reciprocable and vertically movable yarn impinging member mounted therein, a penetrating 85 member carried by said yarn impinging member and movable relatively thereto upon engagement with an impenetrable medium on said filling carrier upon substantial exhaustion of filling, a bell crank lever pivotally mounted upon said impinging member 90 operable by said relative movement to engage a transmitter for causing the actuation of mechanism to effect a change in the operation of the loom, a cam consisting of a member pivotally mounted upon said guide and having an inclined face adapted to engage said bell crank lever and resilient means for permitting a pivotal movement of 95 said cam, and means for adjusting the position of said cam relatively to said bell crank lever.

12. A controlling mechanism for looms comprising a guide, a yarn impinging member mounted in said guide consisting of two 100 chambered complementary halves having a reentrant yarn engaging face slidably mounted in said guide, means for permitting the vertical movement of said member, a yarn impinging member telescopically 105 mounted in the chamber in said penetrating member, a bell crank lever pivotally mounted intermediate of lugs projecting from said complementary halves, one arm of said lever 110 engaging said penetrating member, a spring 115 120

engaging said penetrating member, a spring 125 130

within said chamber engaging said bell crank lever, means for adjusting the compression of said spring and a transmitter adapted to cause the action of mechanism to effect a change in the operation of the loom lying in the path of the other arm of said bell crank lever, whereby upon engagement by said penetrating member with the barrel of the filling carrier upon substantial exhaustion of filling the actuation of said bell crank lever will operate said transmitter to cause a change in the operation of the loom.

13. A feeler for looms comprising a substantially rectangular hollow guide formed in two complementary parts and having flanges adapted to be secured together and to a means of support; a yarn impinging member adapted to feel upon the filling of

an active shuttle, slidably mounted in said guide and having a head provided with 20 curved surfaces bearing upon the end wall of said guide adapted to permit vertical movement of the filling engaging end of said impinging member, a penetrating member telescopically carried by said impinging 25 member and movable relatively thereto and means adapted upon said relative movement caused by the engagement of the impinging member with the barrel of the filling carrier upon substantial exhaustion of filling to 30 initiate the action of mechanism for effecting a change in the operation of the loom.

In testimony whereof, I have signed my name to this specification.

EDWARD S. STIMPSON.
